UNITED STATES PATENT OFFICE.

WOLCOTT A. HULL, OF NEW YORK, N. Y., AND FRANK S. TRUESDELL, OF ANSONIA, CONNECTICUT, ASSIGNORS TO SAID HULL, AND THE ANSONIA BRASS AND COPPER COMPANY, OF ANSONIA, CONNECTICUT.

LAMP-FIXTURE.

SPECIFICATION forming part of Letters Patent No. 283,891, dated August 28, 1883.

Application filed December 29, 1882. (No model.)

To all whom it may concern:

Be it known that we, WOLCOTT A. HULL, of New York, in the county and State of New York, and FRANK S. TRUESDELL, of Ansonia, 5 in the county of New Haven and State of Connecticut, have invented a certain Improvement in Lamp-Fixtures, of which the following is a specification.

This improvement consists in the combination, in a lamp-fixture, of a stationary part, an extensible part, and a telescopic rod, whereby we produce a very compact fixture having an extensible part, which has a very great range of adjustment.

15 The improvement also consists in other features, which will hereinafter be described, and then pointed out in the claims.

In the accompanying drawings, Figure 1 is a side view of a chandelier embodying our improvement. Fig. 2 is a similar view, showing a portion of the parts in a different position in dotted outline. Fig. 3 is a view illustrative of the manner in which certain side arms are fastened to a yoke or cross-piece. Fig. 4 25 is a view illustrative of the manner in which a guide for an extensible part is secured to the side arms; and Fig. 5 is a sectional view illustrative of certain features in the construction of a shade-support and a crown, which is to be 30 used on the shade.

Similar letters of reference designate corresponding parts in all the figures.

A designates two side rods or arms, which extend downwardly in parallel positions for 35 some distance, and then flare outwardly toward the lower ends, where they are provided with means for supporting lamps. These arms are secured at the top to a yoke or cross-piece, B, and near the lower ends they are secured together by means of a guide-piece, C. This guide-piece is provided with sockets or eyes a, which are slipped over the arms and rest upon pins b, which are inserted in the arms. Set-screws c, extending through the sockets 45 and impinging against the arms, serve to maintain the arms and guide-piece in their proper relative positions. At the upper ends of the arms are square or polygonal portions d, which fit in correspondingly-shaped sockets in the 50 yoke or cross-piece B, and above these por-

tions are screw-threaded nipples or terminals e. Nuts f, fitting on these terminals above the yoke or cross-piece, secure the arms and yoke or cross-piece together. A loop, g, is secured to the yoke or cross-piece, for suspending the chandelier.

D designates an extensible part or "harp," which at the lower end supports a lamp and comprises two parallel portions, which extend upward through the guide-piece C. These 60 rods extend through tubes E, preferably made of metal, which fit snugly in holes in the guide-piece, and so guide the parallel portions of the extensible part or harp. At both the upper and lower ends these tubes are provided 65 with collars or flanges h, which preclude them from passing entirely through and out of the guide-piece. When the extensible part or harp is lowered, the tubes descend with it through their gravity, and when the extensible part or harp is raised the tubes are raised by it. The tubes rest upon spiral springs i, which surround the parallel portions of the extensible part or harp above a shade-holder, F, which is attached thereto.

To the upper ends of the parallel portions of the extensible part or harp are attached chains G, which extend upwardly over pulleys j, arranged in the yoke or cross-piece B, thence down around pulleys k, arranged upon 75 a cross-bar attached to a counterbalance-weight, H, and thence upwardly to the yoke or cross-bar, where their ends are fastened. The counterbalance-weight surrounds and travels along a rod, I, which extends between the 80 yoke or cross-piece B and the guide-piece C.

The parallel portions of the extensible part or harp and the tubes E may be regarded as telescopic rods. It will be readily understood that when the extensible part or harp descends 85 the tubes E descend with it until the collars or flanges h at their upper ends come in contact with the guide-piece. The extensible part or harp then descends still farther, the tubes serving to guide it thereafter to the end 90 of its movement. By this means we obtain a great range of movement for an extensible part or harp with short rods; hence the chandelier will be very compact when the extensible part or harp is raised, while the latter part will be 95 100

capable of far more than the usual amount of extension.

Instead of chains, any suitable tackle may be used.

5 The shade-holder is made of sheet metal, and comprises a cylindric or approximately cylindric upper part and a flaring lower portion. The upper part has spring-tongues *l* extending from it, and formed by slitting the metal and bending outward the portions surrounded by the slits. Against these tongues the upper part of the shade *J* rests.

10 *K* is a crown, made of sheet metal and fitted outside the shade. It has affixed to its interior spring-tongues *m*, which are adapted to impinge upon the shade with a resilient pressure.

15 What we claim as our invention, and desire to secure by Letters Patent, is—

20 1. In a lamp-fixture, the combination of a stationary part, an extensible part comprising a telescopic rod, a guide-piece for the rod, and a chain or tackle attached to the lower section of the rod, substantially as specified.

25 2. In a lamp-fixture, the combination of a stationary part, an extensible part comprising a telescopic rod, a guide-piece for the rod, and a chain or tackle attached to the lower section of the rod, pulleys around which the chain or

tackle is passed, and a counterbalance-weight, 30 substantially as specified.

3. In a lamp-fixture, the combination of a stationary part, an extensible part comprising telescopic rods, a guide-piece, chains or tackle attached to the lower sections, the pulleys *j k*, 35 and a counterbalance-weight, substantially as specified.

4. The combination of the extensible part or harp *D*, the tubes *E*, and the springs *i*, substantially as specified. 40

5. The combination of the side rods or arms *A*, the guide-piece *C*, with its sockets or eyes *a*, the pins *b*, and the set-screws *c*, substantially as specified.

6. A shade-holder made of sheet metal, and 45 consisting of an upper approximately cylindric portion and a flaring lower portion, the upper cylindric portion being provided with spring-tongues *l*, formed by slitting the said cylindric portion and bending outward the 50 portions surrounded by the slits, substantially as specified.
